UNITED STATES PATENT OFFICE

CLARENCE VOGT, OF WENONAH, NEW JERSEY

ROLLER SKATE

Application filed February 3, 1932. Serial No. 590,754.

This invention relates to new and useful improvements in skates and has particular relation to skates of the type mounted upon wheels or rollers.

5 The particular object of the invention is to provide a skate as set forth having novel features of construction permitting the person skating thereon to describe curves of substantially small radii, thus enabling the 10 person to execute fancy figures.

Another object of the invention is to provide a skate as set forth having novel features of construction permitting the pivoting of the forward rollers of the skate with respect to the skate proper.

15 Another object of the invention is to provide a skate as described having novel means limiting the arc of pivot of the forward wheels at a plurality of predetermined points.

Another object of the invention is to provide a skate as described having novel suspension means for the rear wheels thereof effecting a relatively flexible connection between the wheels and body of the skate.

20 Another object of the invention is to provide a skate as set forth having means for preventing the pivoting of the front wheels of the skate.

25 Another object of the invention is to provide a skate as described having means at the rear end thereof for the purpose of preventing said skate from sliding from under the person skating thereon.

30 Other features and details of construction are set forth hereinafter and disclosed in the accompanying drawings, in which:

35 Figure 1 is a view in plain elevation of a 40 skate embodying the invention;

Fig. 2 is a view in side elevation of the disclosure in Fig. 1;

Fig. 3 is a view in longitudinal section on line 3—3, Fig. 1;

45 Fig. 4 is a detached view in section on line 4—4, Fig. 3;

Fig. 5 is a detached view in section on line 5—5, Fig. 3; and

50 Fig. 6 is a detached view in perspective of the front wheel bracket and the adjustable

means restricting the pivoting of said bracket within predetermined limits.

Heretofore, fancy figure skating for the most part has been restricted to ice skates and roller skates having but two alinged wheels 55 or rollers. By this invention, I provide a roller skate of the ordinary four wheel or roller variety having novel construction, enabling the person skating thereon to describe fancy figures as in ice skating, and execute 60 turns and other courses within a substantially small radius.

Referring now more particularly to the drawings, a skate made in accordance with this invention comprises front and rear top 65 plates 1 and 2 respectively. In the present instance, the front plate 1 is provided with the customary shoe cleat elements 3 adjacent each side thereof which may be adjusted by means of the threaded element 4 to meet the 70 needs of the particular skater. The rear top plate 2 is provided with the customary back plate 5.

The aforementioned top plates 1 and 2 are mounted upon longitudinal channel members 75 7 and 8 respectively. The forward portion of the channel 7 comprises a circular bearing plate 23 disposed at an angle with respect to the top plate 1 the purpose for which will be set forth in detail hereinafter. The channel 80 8 is similarly provided with depending lugs 9 and 9a which are formed integral therewith with the said lugs being provided with apertures therein for the passage of a pivot pin 10. A channel member 11 is mounted 85 internally of the channel members 7 and 8 and adjustably secured to each of said channels to permit the length of the skate to be varied at the discretion of the skater.

The rear wheels 12 are rotatably mounted 90 upon a shaft or axle 13 which is in turn mounted in the side walls 14 of a bracket 15. The bracket 15 is further provided with up-standing lugs 16 and 16a at the front and rear thereof, the said lugs having apertures therein for the passage of the pivot pin 10 therethrough, constituting a bearing about which the bracket 15 may pivot, thus affording greater flexibility between the wheels 12 and the skate body. 100

Two coil compression springs 17, 17 are disposed intermediate the upper face of the bracket 15 and the channel 8 for the purpose of stabilizing the rocking of the skate and normally maintain said skate in a substantially level position.

A brake bar 18 is mounted on the pivot pin 10 adjacent the rear extremity thereof, and operates against the action of a spring 19 which embraces said pin 10. A roller 20 is rigidly mounted at the lower extremity of the bar 18 and is positioned to just clear the floor or surface on which the skate rests. An arm 21 extends forwardly from the bar 18 and is provided with a curved portion or hook 22 at the forward end thereof which is arranged to engage the axle 13 and limit the rearward movement of the bar 18, which occurs when the roller 20 contacts with the floor or other surface, to prevent the skate from slipping from beneath the person skating thereon.

The forward channel member 11 is provided with a rearwardly inclined bearing plate 23 having an upstanding lug 24 at the forward end thereof, and a centrally disposed aperture 25 for the passage of a pivot bolt 26. The forward rollers 27 are mounted on an axle 28 which is supported in the depending extensions 29, 29 of a bracket 30, the said bracket 30 being disposed substantially parallel to the plate or disk 23.

For the purpose of providing relatively friction free turning of the bracket 30 with respect to the bearing plate 23, it has been found desirable to dispose a plate or disk 31 intermediate the bracket 30 and plate 23, the said plate 31 having suitable openings therein, arranged for the reception of roller bearing elements 32 which contact in the present instance with the aforementioned bracket 30 and bearing plate 23, the plate 31 functioning primarily as a means for maintaining the roller bearings in operative relation with the surfaces of the bracket and the bearing plate. The bracket 30 and the disk 31 are each provided with a center opening for the passage of the pivot bolt 26.

A spring 33 having arms 34 and 35 respectively, embraces the pivot pin 26 adjacent the upper extremity thereof, the forward arms 34 and 35 being arranged to reside in the notches formed in the aforementioned lug 24 and the lug 36 on the front of the bracket 30. The spring 33 functions to yieldingly maintain the bracket 30, and the wheels 27 carried thereby, in normal position, and yet permit the pivoting of the plate 30 about the pin 26 in a direction and degree, depending upon the location and amount of pressure applied to the skate by the skater.

A stop 37 projects upwardly from the rear of the bracket 30 and operates to limit the turning movement of the bracket 30 by en-

gagement with one or the other flanges of the channel member 7.

A channel piece 38 having a slot 39 longitudinally thereof is slidably mounted in inverted relation with respect to and internally of the forward channel member 7 by means of a bolt 40. The forward portion of the channel piece 38 is stepped as at 41 by forming a series of notches of decreasing width inwardly of the said channel. By provision of the novel step arrangement as set forth the degree of turn of the bracket 30 may be restricted within predetermined limits by advancing the channel 38 so that one of the formed steps thereof lies in the path of the stop 37 on the bracket 30. The innermost notch in the channel 38 is of sufficiently narrow width that the bracket 30 will be locked against turning when the notch is engaged by the stop 37. The upper edges of the flanges of the channel 38 are each provided with a raised knob 42 arranged for engagement with a series of recesses 43 in the under surface of the plate 44, the said knobs and recesses being suitably positioned so that upon engagement of corresponding recesses by the knobs a predetermined step 41 will lie in the path of the stop 37 on the bracket 30.

By the arrangement of the bearing plate 23 and the bracket 30 at an angle with respect to the top plate 1, the moment the skater applies pressure to the right or left side of the skate, the bracket 30 will pivot on the roller bearings 32 thus placing the wheels 27 at an angle, the wheels remaining in the turned position only so long as the pressure is applied, and when the pressure ceases or is lessened the spring 33 will return the bracket 30 and wheels 27 to the normal position or positions corresponding to the degree of pressure still existing.

In using the skate which is the subject of this invention, the skater may describe fancy figures and other courses that have heretofore been impossible with the customary type of roller skate. The skate herein described is of substantially rugged construction and provides a skate that is desirable to the public.

While one embodiment of the invention has been set forth for purposes of description, it is not intended to be restricted thereto except as set forth in the appended claims.

I claim:

1. A roller skate including a foot plate comprising front and rear portions, a bearing plate mounted beneath the front end of the forward section and disposed at a rearwardly inclined angle with respect thereto, a bracket, an axle carried by said bracket, wheels mounted on said axle, a pivot pin connecting said bracket and the bearing plate, bearings disposed intermediate the bracket and the bearing plate effecting relatively friction free turning of the bracket and wheels with respect to the foot plate, the direction and de-

gree of turning of said bracket depending upon the location and amount of pressure applied to said foot plate, and a plate intermediate the bracket and the bearing plate having openings therein constituting means maintaining the bearings in operative relation with respect to the bearing plate and the bracket.

2. A roller skate including a foot plate, a bearing plate mounted beneath the front end of said foot plate and disposed at a rearwardly inclined angle with respect thereto, a bracket, an axle carried by said bracket with said bearing plate, bearings disposed intermediate said bracket and the bearing plate effecting relatively friction free pivoting of the bracket and wheels with respect to the foot plate, depending upon the amount and location of pressure applied to said foot plate, and adjustable means restricting the turning of the bracket within at least two predetermined limits.

3. A roller skate including a foot plate, a bracket mounted beneath the rear end of said foot plate, a bearing plate, an axle carried by said bracket, wheels mounted on said axle, a pivot pin passing through said bearing plate and the bracket longitudinally with respect to the skate, and springs disposed intermediate and compressible between the bracket and foot plate restricting the pivoting of said plate and the wheels with respect to the foot plate.

4. A roller skate including a foot plate comprising front and rear portions, a bearing plate mounted beneath the front end of the forward section and disposed at a rearwardly inclined angle with respect thereto, a bracket, an axle carried by said bracket, wheels mounted on said axle, a pivot pin connecting said bracket and said bearing plate, bearings disposed intermediate the bracket and the bearing plate effecting relatively friction free turning of the bracket and wheels with respect to the foot plate, the direction and degree of turning of said bracket depending upon the location and amount of pressure applied to said foot plate, a bracket mounted beneath the end of the rear portion of said foot plate, a bearing plate, an axle carried by said plate, wheels mounted on said axle, a pivot pin passing through said bearing plate and the bracket longitudinally with respect to the skate, and springs disposed intermediate the bracket and bearing plate restricting the pivoting of said plate and the wheels with respect to the foot plate.

5. A roller skate including a foot plate comprising front and rear portions, a bearing plate mounted beneath the front end of the forward section and disposed at a rearwardly inclined angle with respect thereto, a bracket, an axle carried by said bracket, wheels mounted on said axle, a pivot pin connecting said bracket and the bearing plate having openings therein constituting means maintaining the bearings in operative relation with respect to said bearing plate and the bracket, a spring embracing the pivot pin tending to yieldingly maintain the bracket and wheels in normal position, adjustable means restricting the pivoting of

plate, bearings disposed intermediate the bracket and the bearing plate effecting relatively friction free turning of the bracket and wheels with respect to the foot plate, the direction and degree of turning of said bracket depending upon the location and amount of pressure applied to said foot plate, a plate intermediate the bracket and the bearing plate having openings therein constituting means maintaining the bearings in operative relation with respect to the bearing plate and the bracket, a bracket mounted beneath the end of the rear portion of said foot plate, a bearing plate, an axle carried by said plate, wheels mounted on said axle, a pivot pin passing through said bearing plate and the bracket longitudinally with respect to the skate, and springs disposed intermediate the bracket and bearing plate restricting the pivoting of said plate and the wheels with respect to the foot plate.

6. A roller skate including a foot plate, a bearing plate mounted beneath the front end of said foot plate and disposed at a rearwardly inclined angle with respect thereto, a bracket, an axle carried by said bracket with said bearing plate, bearings disposed intermediate said bracket and the bearing plate effecting relatively friction free pivoting of the bracket and wheels with respect to the foot plate, depending upon the amount and location of pressure applied to said foot plate, means arranged for engaging the bracket to prevent the pivoting thereof, a bracket mounted beneath the rear portion of said foot plate, a bearing plate, an axle carried by said plate, wheels mounted on said axle, a pivot pin passing through said bearing plate and the bracket, longitudinally with respect to the skate, and springs disposed intermediate the bracket and bearing plate restricting the pivoting of said plate and the wheels with respect to the foot plate.

7. A roller skate comprising a foot plate and front and rear portions, a bearing plate mounted beneath the front end or forward section and disposed at a rearwardly inclined angle with respect thereto, a bracket, an axle carried by said bracket, wheels mounted on said axle, a pivot pin connecting said bracket and said bearing plate, bearings disposed intermediate the bracket and the bearing plate effecting relative free turning of the bracket with respect thereto, the direction and degree of turning of said bracket depending upon the location and amount of pressure applied to said foot plate, a plate intermediate the bracket and the bearing plate having openings therein constituting means maintaining the bearings in operative relation with respect to said bearing plate and the bracket, a spring embracing the pivot pin tending to yieldingly maintain the bracket and wheels in normal position, adjustable means restricting the pivoting of

the bracket within predetermined limits, a second bracket mounted beneath the rear portion of said foot plate, a bearing plate, an axle carried by said plate and having wheels mounted thereon, a pivot pin passing through said bearing plate and the bracket longitudinally with respect to the skate, and springs disposed intermediate the bracket and the bearing plate constituting means controlling the rocking of said plate with respect to the foot plate.

8. A roller skate including a foot plate, a bearing plate mounted beneath the front end of said foot plate and disposed at a rearwardly inclined angle with respect thereto, a bracket, bearings disposed intermediate said bracket and the bearing plate effecting relatively friction free pivoting of the bracket with respect to the foot plate, depending upon the amount and location of pressure applied to said foot plate, and means intermediate the bracket and the bearing plate having openings therein for maintaining the bearings in operative relation with respect to the bearing plate and the bracket.

9. A roller skate including a foot plate, a bearing plate mounted beneath the front end of said foot plate and disposed at a rearwardly inclined angle with respect thereto, a bracket, bearings disposed intermediate said bracket and the bearing plate effecting relatively friction free pivoting of the bracket with respect to the foot plate, depending upon the amount and location of pressure applied to said foot plate, means intermediate the bracket and the bearing plate having openings therein for maintaining the bearings in operative relation with respect to the bearing plate and the bracket, and adjustable means restricting the turning of said bracket within at least two predetermined limits.

10. A roller skate including a foot plate comprising front and rear portions, a bearing plate mounted beneath the front end of the forward section and disposed at a rearwardly inclined angle with respect thereto, a bracket, an axle carried by said bracket, wheels mounted on said axle, a pivot pin connecting said bracket and the bearing plate, bearings disposed intermediate the bracket and the bearing plate effecting relatively friction free turning of the bracket and wheels with respect to the foot plate, the direction and degree of turning of said bracket depending upon the location and amount of pressure applied to said foot plate, and adjustable means restricting the turning of the bracket within at least two predetermined limits.
